US00D881936S

(12) **United States Design Patent** (10) Patent No.: **US D881,936 S**
(45) Date of Patent: **** Apr. 21, 2020**

(54) **DISPLAY SCREEN OR PORTION THEREOF WITH GRAPHICAL USER INTERFACE**

(71) Applicant: **Maschinenfabrik Reinhausen GmbH**, Regensburg (DE)

(72) Inventor: **Philipp Meixner**, Regensburg (DE)

(73) Assignee: **MASCHINENFABRIK REINHAUSEN GMBH**, Regensburg (DE)

(**) Term: **15 Years**

(21) Appl. No.: **29/705,275**

(22) Filed: **Sep. 11, 2019**
